H. H. KEITH.

DENTAL CHAIR.

No. 367,300.

Patented July 26, 1887.

FIG. I.

FIG. II.

FIG. III.

FIG. IV.

Attest:

Goddard Whealock
H. B. Knight

Inventor:

Henry H. Keith,
By H. B. Knight, his Atty.

UNITED STATES PATENT OFFICE.

HENRY H. KEITH, OF ST. LOUIS, MISSOURI.

DENTAL CHAIR.

SPECIFICATION forming part of Letters Patent No. 367,300, dated July 26, 1887.

Application filed April 29, 1886. Serial No. 200,607. (No model.)

To all whom it may concern:

Be it known that I, HENRY H. KEITH, of the city of St. Louis, in the State of Missouri, have invented a certain new and useful Im-

5 provement in Dental Chairs, of which the following is a full, clear, and exact description, reference being had to the accompanying drawings, forming part of this specification, and in which—

10 Figure I is an outline perspective view of a dental chair (known as the "Morrison chair") having my improvement. Fig. II is an enlarged perspective view of the hand-crank. Figs. III and IV are enlarged details showing 15 the ratchet-wheel with the spring-dog and cam in their different positions.

In dental chairs there are appliances for raising and lowering the seat-frame and its appendages, the appliance being generally 20 turned by a hand-crank.

My improvement consists in the peculiar construction of the crank, enabling it to be worked by the foot.

A is the frame of a dental chair, and B the 25 seat-frame, of which the foot-rest C, back D, and arms E are appendages.

At F are cog-racks on the upright of the main frame, with which engage spur-wheels upon the shaft G, which has journal-bearings 30 on the seat-frame B, so that by the turning of the shaft the seat, with its appendages, may be raised or lowered. The shaft has a ratchet-wheel, H, which engages with a dog or pawl, I, that acts to support the seat at any desired 35 elevation by preventing the rotation of the shaft G in the direction to admit of such descent, while at the same time the shaft is permitted to turn in the other direction for the elevation of the chair-seat. These parts may 40 have any usual construction. No novelty is claimed in them, nor is any detailed description needed, as they are well known, (for instance, in the Morrison dental chair, described in his reissued patent, dated May 15, 1887.)

45 Upon the angular end G' of the shaft is fitted the hand-crank. This has a ratchet or notched wheel, J, whose socket *j* fits the end G', and which turns in the head K of the crank.

L is a pawl or dog, whose end *l* is forced

into the notches of the wheel J by a spring, 50 M, so as to enable the turning of the shaft G by the crank in a direction to raise the seat-frame.

N is a cam turning in the head to hold the pawl L out of engagement with the wheel 55 J when desired. (See Fig. III.) The cam acts on a projection, *l'*, of the pawl when in the position shown in Fig. III; but when in the position shown in Fig. IV the pawl is allowed to engage the wheel J. The cam is turned by 60 a thumb-piece, n.

O is the shank of the crank and P is the handle. R is a stirrup hung onto the handle to give means for working the crank by the foot 65 of the operator.

It will be understood that the hands of the operator may be engaged when it is desired to lift the seat; and at such times it can very easily be done by applying the foot to the crank and imparting to it an oscillatory movement. 70

The weight of the chair, it will be understood, is always sufficient to carry it down when the dog I has been raised and the hand-crank allowed to turn backward.

75 The ratchet connection has great advantages over a simple crank in this connection, as it can at any time be placed in any position out of the way of the operator, and need never be used in a position where the strength of the operator would be expended at a disadvantage.

I claim as my invention—

1. The combination, with the elevating-shaft of a dental chair, of a hand-crank provided 85 with a receptacle for the foot separate from the handle, whereby a combined foot-lever and hand-crank is produced, substantially as set forth.

2. The combination, with a hand-crank having a handle, of a stirrup depending from said handle, substantially as and for the purpose set forth. 90

HENRY H. KEITH.
